Patented Nov. 26, 1963

196,963

PULL

La Verne E. Clayton, Rockford, Ill., assignor to Amerock
Corporation, Rockford, Ill., a corporation of Illinois

Filed May 14, 1963, Ser. No. 74,870

Term of patent 14 years

(Cl. D10—8)

FIG. 2 is a top plan view of the pull.

FIG. 3 is a perspective view of the pull.

FIG. 4 is an enlarged sectional view taken along the line 4—4 in FIG. 2.

FIG. 5 is a side elevation of the pull as viewed from the left in FIG. 1.

FIG. 6 is an enlarged sectional view taken along the line 6—6 in FIG. 2.

I claim:

The ornamental design for a pull, substantially as shown.
